UNITED STATES PATENT OFFICE.

LEVIN O. CORKRAN, OF RHODESDALE, MARYLAND.

SCREEN CLEANER.

Application filed December 6, 1926. Serial No. 152,987.

My invention relates to improvements in screen cleaners, and it consists in the combinations, constructions and arrangements herein described and claimed.

An object of the invention is the provision of a simple, reliable and efficient cleaner for a screen through which a spraying mixture, paint, or like fluid substance passes in a conduit of a sprayer or like device, whereby rupture of or injury to the screen will be obviated when the mixture is forced through the screen under a considerable pressure and a nozzle or discharge member having a relatively small discharge orifice can be employed without likelihood that such discharge orifice will be clogged.

A further object of the invention is the provision of a screen cleaner of the character described which will not offer any objectionable obstruction to the passage of a spraying mixture or like substance in the conduit in which the device is located toward the associated screen.

Other objects and advantages of the invention will be apparent from the following description, considered in conjunction with the accompanying drawings, in which

Figure 1 is a longitudinal section through a screen cleaner embodying the invention,

Figure 2 is a section substantially along the line 2—2 of Figure 1,

Figure 3 is a section substantially along the line 3—3 of Figure 1, and

Figure 4 is a perspective view of a clamp that is used in the device.

The improved screen cleaner comprises a tubular body 1 which may have an integral head 2 at one end thereof. The body 1 may have an outwardly extending flange 3 at its other end and may be closed at its last named end by a removable head 4 that is provided with a marginal rabbet 5 in its inner face for the reception of a packing ring 6 which will be pressed firmly against the flanged adjacent edge of the body 1 when the head 4 is secured to the body 1 by a clamp that is generally indicated at 7, and is illustrated to advantage in Figure 4. The clamp 7 comprises a substantially U-shaped frame 7^a having a web adapted to extend across the head 4 and a pair of arms adapted to straddle the head 4 at diametrically opposite points, the arms of the frame member 7^a being provided at their extremities with in-turned lugs 8 which are adapted to engage under the flange 3 of the body 1. A clamping screw 9 is

threaded through the central portion of the web of the frame 7^a and will cooperate with the lugs 8 on the arms of the frame 7^a to secure the head 4 firmly in place against the adjacent end of the body 1 when the screw 9 has been tightened against the central portion of the head 4 and the lugs 8 are in contact with the inner face of the flange 3 at points diametrically opposite of the latter.

The head 2 is formed with an internal central boss 10. The boss 10 terminates within the body 1 short of the plane of an internal shoulder 11 which faces toward the head 4. The boss 10 is provided with a central bore 12 in which a shaft 13 is journaled. The shaft 13 extends through a stuffing box 14 which is engaged with the enlarged outer end portion of the bore 12. The shaft 13 is held against outward axial movement in the boss 10 by a plate 15 which rests against the inner end of the boss 10 and is secured to the shaft 13 by a cap screw 16 or like fastening device. The outer end portion of the shaft 13 carries a bevel gear 17. A bevel gear 18 on a drive shaft 19 is in mesh with the gear 17 and is disposed between the latter and the head 2 and thus cooperates with the plate 15 to prevent any appreciable axial movement of the shaft 13 in the boss 10. The drive shaft 19 is journaled in a bearing 20 which may be a suitably apertured arm of a bracket 21 that is integral with the body 1 at one edge of the head 2.

The tubular body 1 is provided intermediate the plane of the shoulder 11 and the removable head 4 with a lateral outlet opening 22 which may be provided with internal screw threads for engaging with the screw threaded end portion of a pipe 23. The tubular body 1 also is provided with a lateral intake opening 24 which is located intermediate the plane of the plate 15 and the plane of the shoulder 11. The intake opening 24 may be threaded engaged by a supply tube 25. The tubular body 1 also may have a lateral cleanout opening 26 which is located adjacent to the plane of the inner face of the head 2. The clean-out opening 26 may have internal screw threads for engaging with an end portion of a drain or clean-out pipe 27, or a plug, not shown.

A screen member 28 of relatively fine mesh fits snugly in an end portion of the tubular body 1 against the shoulder 11 and a second screen member 29 of the same size as the screen member 28 but of coarser mesh fits in

the tubular body 1 against the screen member 28. Such screen members will be clamped firmly against the shoulder 11 by a ring 30 which fits in the tubular body 1 between the marginal edge portions of the screen members and the head 4 and receives sufficient pressure from the head 4 when the latter is secured in place on the flanged end of the body 1 to firmly secure the marginal edge portions of the screen members 28 and 29 in place against the shoulder 11. The ring 30 has a lateral opening 31 in register with the aforesaid outlet opening 22.

The plate 15 is provided on its inner face with a pair of studs 32 which respectively are joined to diametrically opposite portions of the plate 15 and are located parallel with and equi-distant from the extended axial line of the shaft 13. The studs 32 terminate a substantial distance from the screen member 28. A brush that is adapted to be used in the device has a back 33 and bristles 34, the back 33 being provided adjacent to its opposite ends with openings 35 for the reception of the free end portions of the studs 32 and the bristles 34 being of sufficient length to be pressed firmly against the screen member 28 as a result of the action of expansion springs 36 on the brush back, the expansion springs being coiled about the studs 32 between the plate 15 and the brush back 33. The studs 32 and the springs 36 preferably are of sufficient length to support the brush back 33 in a plane intermediate the screen member 28 and the intake opening 24 and the brush back is provided at its approximate center with an opening 37 of substantial area through which liquid may pass from the intake opening 24 to the bristles of the brush. The brush back is of less area in cross section than the space within the tubular body 1 so that the liquid mixture that enters the intake opening 24 also may pass around the brush back to the bristles and also to the screen.

From the foregoing description of the various parts of the device, the operation thereof may be readily understood. The device is particularly well adapted for use in a machine for discharging a spraying mixture onto vegetables, trees, or the like, or for spraying paint. It is desirable in making use of a spraying machine of the character referred to that the discharge member or nozzle have a relatively small discharge orifice and it has been found in actual practice that such discharge orifice will be clogged and closed after the machine has been in use but a relatively short time unless the mixture is thoroughly strained or filtered before reaching the nozzle. In order to effect such straining or filtering of the mixture, a screen of relatively small mesh must be used and it is essential that an efficient screen cleaner be employed to prevent clog-

ging and stoppage of the screen if the operation of the sprayer is to be satisfactory.

In making use of the device, the mixture that is to be screened enters the tubular body 1 through the intake opening 24 and passes through the screen 28-29 to the outlet 22. Motion may be imparted to the shaft 19 in any suitable known manner and the rotation of the shaft 19 will cause turning of the shaft 13 and of the brush. The bristles of the brush will be moved in circular paths in contact with the screen and will have a wiping action on the screen which will prevent clogging of the orifices of the screen and also will serve to dislodge from the screen any hard particles which are too large to pass through the meshes of the screen member 28. The tubular body 1 preferably will be disposed upright during the operation of the device so that the annular space between the boss 10 and the tubular body will serve as a trough for the reception of the particles which are too large to pass through the mesh of the screen member 28. The matter that has accumulated in the body 1 between the boss 10 and the inner wall of the body can be removed through the clean-out opening 26 and the pipe 27 when desired, it being understood that the clean-out opening 26 or the pipe 27 adjacent to the clean-out opening 26 normally is closed by a suitable plug or valve, not shown, or in any other suitable known manner. Obviously, the invention is susceptible of embodiment in forms other than that which is illustrated in the accompanying drawings, and I therefore consider as my own all such modifications and adaptations thereof as fairly fall within the scope of the appended claims.

I claim:

1. A screen cleaner comprising a hollow body having an inlet and an outlet, a screen disposed within said hollow body between said inlet and said outlet, a rotary shaft extending into said hollow body on the inlet side of said screen, a pair of spaced studs supported on said rotary shaft and operable by said shaft, said studs having free end portions, and a brush having openings in its back for the reception of the free end portions of said studs and having bristles in contact with said screen, said brush back having a central opening through which material may pass from said inlet to said screen.

2. A screen cleaner comprising a hollow body having a head at one end provided with an internal central boss and having an annular shoulder spaced from the plane of the end of said boss, said hollow body having an inlet opening located at the same side of said annular shoulder as said boss and an outlet located at the other side of the plane of said annular shoulder, said inlet opening disposed in a plane which is located between the

upper end of the boss and the shoulder, a screen secured against said annular shoulder through which liquid must pass from said inlet to said outlet, said boss having a central bore, a shaft journaled in said bore, a plate secured to the inner end of said shaft having a pair of extending spaced studs respectively located at opposite sides of and equi-distant from the extended axial line of 5 said shaft, and a spring pressed brush having openings in its back slidably receiving said studs and having bristles in contact with said screen.

3. A screen cleaner comprising a hollow body having a head at one end provided with an internal central boss and having an annular shoulder spaced from the plane of the end of said boss, said hollow body having an inlet opening located at the same side of said 10 annular shoulder as said boss and an outlet located at the other side of the plane of said annular shoulder, said inlet opening disposed in a plane which is located between the upper end of the boss and the shoulder, a screen secured against said annular shoulder through which liquid must pass from said inlet to said outlet, said boss having a central bore, a shaft journaled in said bore, a plate secured to the inner end of said shaft 15 having a pair of extending spaced studs respectively located at opposite sides of and 20

equi-distant from the extended axial line of said shaft, and a spring pressed brush having openings in its back slidably receiving said studs and having bristles in contact with said screen, said hollow body also having a clean-out opening located adjacent to said head at one end of said hollow body. 25

4. A screen cleaner comprising a hollow body having a head at one end provided with an internal central boss and having an annular shoulder spaced from the plane of the end of said boss, said hollow body having an inlet opening located at the same side of said annular shoulder as said boss and an outlet 30 located at the other side of the plane of said annular shoulder, a screen secured against said annular shoulder through which liquid must pass from said inlet to said outlet, said boss having a central bore, a shaft journaled in said bore, a plate secured to the inner end of said shaft having a pair of extending spaced studs respectively located at opposite sides of and equi-distant from the extended axial line of said shaft, and a spring pressed brush having openings in its back slidably receiving said studs and having bristles in contact with said screen, said brush back also having a central opening for the passage of liquid from said inlet to said screen. 35 40 45 50 55
